Primary Examiner — Sandra Snapp*(74) Attorney, Agent, or Firm* — Litts Law Firm(57) **CLAIM**

The ornamental design for a personal massager, as shown and described.

DESCRIPTION

FIG. 1 is a front perspective view of a personal massager showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines in the figures are for environmental purpose only and form no part of the claimed design.
